UNITED STATES PATENT OFFICE.

EDMUND SUCKOW, OF BUFFALO, NEW YORK.

CURRENT-MOTOR.

SPECIFICATION forming part of Letters Patent No. 397,097, dated January 29, 1889.

Application filed February 27, 1888. Serial No. 265,388. (No model.)

To all whom it may concern:

Be it known that I, EDMUND SUCKOW, a citizen of the United States, residing at Buffalo, in the county of Erie and State of New York, have invented new and useful Improvements in Current-Motors, of which the following is a specification.

My invention relates to current or tide-wa-
ter motors, and the purpose thereof is to pro-
vide a novel construction and arrangement of
parts whereby a greatly-increased length of
the wing-belt may be practicable and a cor-
responding increase of power attainable.

It is my purpose, also, to provide means
whereby the belt-drums may be raised out of
the current by the motive power of the mech-
anism, and to combine therewith simple and
readily-operated apparatus whereby, when
desired, the drums may be both raised and
lowered without exercise of manual power.

It is my further purpose to provide an im-
proved construction of cable belt which may
be substituted for the link belt heretofore
used, whereby greater flexibility is secured
and the construction of the mechanism con-
siderably simplified.

It is my further purpose, also, to provide a
novel, simple, and secure manner of fastening
the ends of the cables forming said belt and
to simplify the construction of the parts
forming such belt.

It is my purpose to provide a motor capable
of use in tide-water, and to combine therewith
means whereby the axes of the drums carry-
ing the continuous belt of the motor may be
inclined in two directions relatively to the
ebb and flow of the tide to present the wings
or vanes of the belt to the force of the cur-
rent or flow in such manner and at such an
angle that the weight of the belt shall be in
part sustained by the force of said current,
thereby permitting a material increase in the
length of said belt.

My invention also contemplates the provi-
sion of suitable means for imparting a proper
tension to the belt, and the combination, with
the shaft, of anti-friction carriages upon
which said shafts have bearing, whereby the
necessary adjustments for tension and to se-
cure a proper angle of the vanes of the belt

relatively to the line of action of the current
may be speedily and easily effected without
undue wear and tear of the operative parts.

The invention consists in the several novel
features of construction and new combina- 55
tions of parts hereinafter fully set forth, and
then definitely pointed out in the claims.

In the accompanying drawings, Figure 1 is
a view showing the belt in plan and the two
drums in horizontal section, the plane of sec- 60
tion of the drum at the left being in the line
x *x*, Fig. 2, and that of the other drum in the
line *y* *y* of said figure. Fig. 2 is a view partly
in central vertical section and partly in ele- 65
vation in Fig. 1. Fig. 3 is a front elevation
of the complete apparatus organized as a cur-
rent-motor. Fig. 4 is an elevation taken from
the left-hand end of Fig. 3. Fig. 5 is an end
elevation showing the adaptation of the mech- 70
anism to a tide-water motor. Fig. 6 is a plan
view of the lower part of Fig. 5, the shaft and
drum being removed. Fig. 7 is a detail plan
view of a section of the link belt. Fig. 8 is
a detail plan view of a portion of the cable 75
belt, showing also the manner of uniting the
ends of the cables. Fig. 9 is a detail eleva-
tion of one of the cross-braces of the cable
belt detached. Fig. 10 is a partial plan of the
friction-clamp mechanism for bringing into 80
action the devices for raising and lowering
the drums by the power of the current. Fig.
11 is a detail plan of the modified construc-
tion of clamp for raising the drums by the
power of the current, the lowering being ef- 85
fected by manual power. Fig. 12 is a detail
view of the universal bearing for the arm of
the lever operating the friction-clamp. Fig.
13 is a bottom plan of one of the shaft-car-
riages. Fig. 14 is a side elevation of a motor 90
applied to a falling current.

In the said drawings, the reference-numeral
1 denotes the shaft upon which the drums
carrying the motor-belt are keyed. These
shafts are each provided with a journal-pin,
2, which is stepped into a suitable bearing, 4, 95
said bearing being either movable, as herein-
after described, or rigid. The lower end of
the shaft rests in a ring, 5, having friction-
rolls 6, which run upon the base or support 4,
an opening being formed in a socket, 7, car- 100

ried by said ring to permit the journal-pin to pass through and engage the aperture in the bearing 4.

Upon each shaft 1 is keyed in any manner 5 a drum, which may consist of parallel heads 8, inclosing a cylindrical body, 9, with the heads projecting sufficiently to form suitable flanges, 10. I may, however, substitute for the cylindrical body spiders 12, having a fork, 13, at the extremity of each arm to engage with the cross-braces of the belt. If the cylindrical body 9 is employed, it is provided with transverse channels 14, having sprocket-teeth 15, to partly embrace the cross-braces.

5 It should be noted that the cylindrical form is especially adapted to the use of the cable belt, while the spiders are preferably used with the link belt shown in Fig. 1.

The link belt consists of a series of similar frames composed of side bars, 16, pivotally coupled together at their ends by cross-braces 17. Upon each cross-brace is hinged a wing or vane, 18, composed of a flat plate of metal or other material connected by flexible fastenings 19 to the side bars, 16, said fastenings being attached at any suitable point between the ends of the vane. I have shown the hinge-connections 20 as looped upon the cross-braces; but I may substitute therefor any suitable form of fastening—such, for example, as that shown in Fig. 8, and consisting of loops 21 upon the vane engaging with eyes 22 on the cross-brace. The link belt thus formed is continuous, running over both drums, and 5 of any desired length. It may, if preferred, consist of a double series of vanes arranged in pairs, as in Fig. 7, the members of each pair being separated by a central bar, 16^a.

Upon the lower flange of the drum, at suitable intervals, I mount friction-rolls 23, upon which the edges of the belt may ride as it comes upon and leaves the drum, thereby taking off the wear caused by the gravitation of the belt upon the drum. Upon the upper 5 part of such shafts 1 is mounted a pulley, 24, from which power derived may be transmitted to any suitable mechanism; but, if preferred, a gear may be substituted for the pulley. The drums being usually of considerable diameter 5 and correspondingly heavy, it is essential to provide means whereby they may be raised to a point where they as well as the belt may be accessible for repair, inasmuch as I have provided for sinking these parts, when in operation, far enough below the surface to obviate all danger from floating ice or other matters, as well as from navigation. To effect this result I have provided the following means:

Tapped through suitable bearings, 44, upon 5 the drum are screw-shafts 26, each keyed to a pinion, 27, the screw-shaft having beneath said pinion a collar, 28, which rests upon a disk, 29, keyed to the shaft 1. Each of these pinions meshes with an internally-geared annulus, 30, which is mounted on the disk 29, and may turn in a groove or channel, 31, formed therein. The periphery of the annu-

lus 30 is provided with a groove, 32, in which is laid a friction-clamp band, 33, having lugs 34, Fig. 10, upon its ends, through which a screw, 35, is tapped, the thread of said screw engaging with a female thread in one lug, while the other lug is simply swiveled upon the end of the screw. A crank-arm, 36, on the latter enables the operator to tighten the clamp-band and thereby hold the gear annulus from rotation with the disk 29, thereby compelling the pinions 27 to rotate. Both pinions also mesh with a central gear, 37, mounted upon a hub, 38, which is slipped 80 upon the shaft and rests upon the disk 29. This hub has a disk, 39, rigid therewith and provided with a clamp-band, 40, and a clamp-operating screw, 41, similar to that already described in connection with the disk 29. 85

It will readily be seen that by locking the gear-annulus, the center gear, 37, being free, the pinions 27 will be rotated in one direction, while by locking the disk 39, and thereby arresting the center gear, 37, said pinions will 90 be rotated in the opposite direction, thereby revolving the screw-shafts and raising and lowering the belt-drums by the force of the current.

Inasmuch as the labor involved in lifting 95 the drums is much greater than that required to lower them, I may use a single screw-shaft only, as shown in Figs. 3 and 12. This shaft 42 lies in a channel, 43, in the shaft 1, and its thread meshes with nuts or other bearings 44 100 on the drum. When this construction is adopted, a friction-disk, 45, is mounted upon the upper end of the screw-shaft, which projects through the pulley 24 eccentrically to the axis of the latter. This disk is provided 105 with a lower flange, 46, Fig. 11, upon which rests a clamp-band, 47, which surrounds the edge of the disk. One end of this clamp-band is rigidly secured to an arm, 48, which rests on the flange 46, while the other end is 110 attached to the end of a lever, 49, having a fulcrum in lugs 50 on the arm 48. By drawing the lever-arm over, the disk 45 will be locked and the drum will, as the shaft continues its revolutions, be forced to climb the 115 screw-shaft 42. Upon the disk 45 are formed lugs 51, having openings 52 for the insertion of hand-spikes, whereby the screw-shaft may be revolved to lower the drum. The arm 48 is mounted on a bar, 53, which is secured in 120 a bearing, 54, hereinafter more particularly described.

In place of the link belt described, I may use the cable belt shown in Fig. 8. This belt consists of two parallel cables, 55, of wire or 125 other suitable material, having at intervals cross-braces 56, the extremities of which are forked to partly embrace said cables, a rivet-pin, 57, being inserted in the branches of the fork and passing through the cable. Each 130 cross-brace is provided with eyes 22, with which loops 21 engage, said loops being riveted to the plates forming the vanes of the belt, which are limited in their swinging

movement by chains or other flexible connections, 19.

Where the ends of the cables 55 meet, their union is formed by extending said ends past each other by a distance equal to the space between two of the cross-braces. The prolonged ends are laid in the slightly-deepened forks 61 of a cross-brace, 62, and are then crossed and extended to the forked ends of a similar cross-brace, 63, where they are fastened by rivets 64. The other ends of the cables are laid in the forks of the cross-brace 63, outside the extremities of the crossed portions, and are carried straight to the ends of the cross-brace 62, where they are fastened by rivets 65. Within the space occupied by the crossed ends of the cables no vane is placed. The construction described gives a simple form of fastening, which imparts great strength and security to the joint.

I propose to incline the shafts of the motor instead of placing them vertically, in order that the force of the current may exert a lifting-power upon those portions of the belt between the drums. In waters having a constant flow in one and the same direction this inclination, having been once adjusted to the rapidity of the current, will not require material alteration afterward. In tide-water motors, however, where the direction of the current is reversed each day, the shafts require to be inclined part of the time in one direction and part of the time in the opposite direction. It is also desirable at times to adjust one of the drums in such manner as to take up any slack in the belt, and for these purposes I have provided the following means: The journal-pin 2 of the adjustable shaft has bearing in an aperture in a shaft-carriage, 66, upon which the ring 5 rests, said carriage being mounted upon friction-rolls 67, consisting of cylindrical bars grooved circumferentially to engage with ribs or lugs 68 on the bottom of the carriage, whereby said rolls are held in place and permitted to turn freely. The shaft-carriage rolls upon a base, 69, which is inclined, as in Fig. 4, to suit the required inclination of the shaft. A swivel or other bearing, 70, supports the upper part of the shaft 1. This bearing consists of a collar surrounding the shaft and having an arm, 71, which projects inward toward a pier, abutment, or other support, 72, upon which is mounted a horizontal flanged rail, 73, engaging the lower edge of a flat plate, 74, formed or mounted on the arm 71. A similar flanged rail, 75, overlaps the upper edge of the plate, which is free to move in either direction between said rails. A similar bearing, 76, having a similar arm, 77, and similarly supported between rails 78, is applied to the lower portion of the shaft 1, above the shaft-carriage 66.

Journalized in suitable bearings, 79, upon the abutment or other support, 72, are screw-shafts 80, tapped through the arms 71 and 77, or through bearings attached to said arms. Upon each shaft is a gear, 81, meshing with

a worm, 82, upon a vertical shaft, 83, supported in bracket-bearings 84, and having a hand-wheel, 85, at the top, whereby it may be revolved. By reference to Figs. 3 and 4 it will be seen that by operating the shaft 83 the motor-shaft and its drum may be moved in either direction and the tension of the belt adjusted to the requirements of each case. In this construction, where the inclination of the shaft is not materially changed, the base 69 may be provided with guides or rails 86, between which the shaft-carriage 66 moves.

In cases where the motor is adapted to use in tide-waters provision must be made for adjusting the shaft 1 of the motor in both directions to incline the vanes of the belt to the ebb and flow, respectively, and this adjustment must be made independently of the adjustment for tension, already described. For this purpose, therefore, I form a trunnion-bearing, 87, upon the shaft, which rests in a fork, 88, on the upper arm, 71, Fig. 5. At its lower end this shaft turns upon its journal-pin 2 and rests upon the ring 5, which turns upon the shaft-carriage 66. Inasmuch as the inclination of the shaft to the flow of the current must be radial, or in the arc of a circle struck from the trunnion-bearing 87, I form the base 89, upon which said carriage moves, in the arc of a circle having a suitable curve, and arrange the carriage 66 so that its friction-rolls will ride upon the concave surface. The adjustment for tension being less frequent and the friction-rolls 67 offering but little resistance, the carriage is moved in the direction of the length of said rolls to tighten and loosen the belt, as will be more fully set forth hereinafter.

Upon the plate 90, sliding between the flanged rails 78 upon the support 72, is a bracket-frame, 91, extending across the concave base 89 and curved concentrically therewith. The other end of the frame is attached to a slide-plate, 92, moving between rails 93, formed or mounted on a support, 94, rising from the base, said rails being parallel with the rails 78.

The curved portion of the frame 91 is provided with a channel or slot, 95, through which tie-bolts 96 extend. Within this channel lies a block, 96^a, the edges or sides of which are flush with the lateral or outer surfaces of the curved bars of the frame, the construction closely resembling that of the cross-head of an engine. The bolts 96 pass through a plate, 97, having its upper edge lying upon or against the upper edge of the frame above the channel 95 and through the slide-block 96^a, and the lower edge of said plate clamps upon the side of the shaft-carriage. A flanged bearing, 98, embraces the lower end of the shaft above the ring 5, and the halves of the ring being bolted together, depending lugs 100 are formed upon the meeting parts, which lugs drop over and close firmly upon the ends of the shaft-carriage 66. By these devices the carriage is compelled to move with the shaft

- in all directions. In brackets 101 are journaled screw-shafts 102, tapped through the ends of the bracket-frame 91. These shafts are provided with worm-gears 103, moved in unison by a worm-shaft, 104, having a miter-gear, 105, at its end. This miter meshes with a second miter on the vertical shaft 106, having a hand-wheel by which it is turned. The screw-shafts effect the adjustment by which the tension is regulated, the upper bearing being moved simultaneously in the manner already set forth. The change of inclination is effected by the ebb and flow of the tide, the shafts and drums swaying back and forth with each change.
- 15 The side of the frame 91, next the closed supporting-shaft, is provided with an arch, 91^a, to impart additional strength to resist the tension of the belt and the draft thereon caused by the power of the current.
- 20 As the arm or bar 53 of the friction-clamp band 47 is raised and lowered by the change of inclination described, I construct the bearing 54, in which it is mounted, with trunnion-bearings 107, journaled in a ring, 108, the latter having a bar, 109, depending from it and lying in a socket, 110, in which it rises and falls, as seen in Fig. 5. With a tide-water motor both shafts must be adjustable as to inclination; but as to tension it is sufficient to adjust one of said shafts only, as seen in Fig. 3.
- 25 It is evident that I may use this motor in a cataract or fall, as well as in other parts of the current, the only change being in the form of bearings for the ends of the shaft.
- 30 The operation of the motor is obvious. The entire belt, save those portions in contact with the drums, is exposed to the action of the current, as shown in Figs. 1 and 3. The inclination of the shafts, whereby the current strikes 35 the vanes at a vertical as well as a horizontal angle, bears the long sections of belt stretched between the drums upward, supporting their weight, or so nearly so as to enable the length of the belt to be very greatly extended.
- 40 Openings or recesses 112 may be formed in the drum 9 when the cylindrical body is used, lying partly in the lower flange, 8, and partly in the body 9. These openings receive the chains or flexible connections, limiting the 45 outward swing of the vanes of the belt.
- 45 Clearers or scrapers 113, Figs. 3 and 4, may be mounted upon the pier or other support 72, in proximity to the drums, to remove weeds or other obstructions from the same. These clearers are provided with an angle or edge, 50 which is inclined to the line of travel of the belt, whereby any rubbish, weeds, or other débris adhering to the wings will be removed, the angular position of the clearer acting in a manner analogous to a shearing-edge and carrying off foreign matters toward the bottom.
- 55 The shaft-carriages at the lower ends of the drum-shafts and the way or base upon which they move are inclosed by guard-easings 114, 60 which are coextensive with the base-support and effectually protect the parts from ac-

cumulations of sand, sinking materials, and other obstructions.

What I claim is—

1. In a current-motor, a pair of shafts having independent support and carrying drums connected by a belt having vanes capable of a limited outward deflection, the axes of said shafts being inclined contrary to the direction of the current, substantially as described. 75
2. In a current-motor, the combination, with a pair of shafts mounted upon independent supports and having their axes inclined against the direction of the current and provided with drums keyed upon said shafts, of a belt connecting said drums and provided at intervals with vanes hinged to cross-braces upon the belt and having flexible fastenings connecting the sides of said vanes to the parallel members of the belt, substantially as de- 80 scribed. 75
3. In a current-motor, the combination, with inclined shafts mounted upon independent supports and having drums keyed or mounted thereon, of a belt connecting said drums and 90 formed of parallel cables having cross-braces at intervals and provided with vanes hinged to said cross-braces, substantially as de- scribed. 90
4. In a current-motor, the combination, with two shafts having suitable drums keyed thereon, of screw-shafts tapped through bearings on each drum and having pinions meshing with a central gear loose on the drum-shaft, and with an outer gear-annulus and 100 means for arresting the rotation of either said gear or gear-annulus for revolving said pinions in either direction to raise and lower the drums and the belt carried thereby by the power of the current, substantially as de- 105 scribed. 95
5. In a current-motor, the combination, with the vertical shafts mounted upon independent supports and drums carrying the belt, of movable bearings upon which the lower ends of 110 said shafts are stepped, said bearings swinging in the direction of the flow of the current, and stationary bearings for the upper portions of said shafts to secure an automatic inclination of the shafts against the current, 115 substantially as described. 115
6. In a current-motor, the combination, with shafts mounted upon independent supports supporting a belt stretched transversely to the current, of a traveling shaft-carriage supporting the lower ends of said shafts and moving with the current, means for imparting a pivotal support to the upper portion of said shafts, and screw-shafts geared to operate in substantial unison to adjust one of said shafts 120 in a direction transverse to the flow of the current to vary the tension of the belt, substantially as described. 125
7. In a current-motor, the combination, with a pair of inclined shafts having drums which sustain the belt by which power is communicated, of screw-shafts tapped through nuts on 130

said drums, disks keyed on said drum-shafts and giving bearing to the upper ends of said shafts, an intermediate toothed gear-annulus free to revolve on said disk, pinions on the 5 screw-shafts gearing with said annulus, and a central gear, also meshing with said pinions and carried by a loose hub mounted on the shaft and having a disk and friction-clamps independently connected with both disks, 10 whereby either may be arrested while the other revolves, substantially as described.

8. In a current-motor, the combination, with one of the shafts having a drum to carry the motor-belt, of a shaft-carriage in which said 15 shaft has a step-bearing, arms having split rings or collars embracing said shaft below and above and each provided with a slide-plate moving in flanged rails mounted on a suitable support near said shaft, parallel 20 screw-shafts tapped through said arms and having worm-gears at their ends, and a worm-shaft having a hand-wheel, substantially as described.

9. In a current-motor, the combination, with a shaft supporting one of the drums carrying 25 the motor-belt, of screw-shafts tapped through nuts on said drum, a disk rigid on the drum-shaft in which said screw-shafts have bearing, an internally-geared annulus resting on said disk and meshing with pinions on the ends of the screw-shafts, a central pinion meshing 30 with said pinions and carried by a hub loose on the drum-shaft and provided with a disk, an independent friction-clamp on the annulus and another on the disk, and means for operating said clamps alternately to arrest the revolution of said annulus and disk, whereby the drums are raised and lowered by the power derived from the current, substantially 35 as described.

In testimony whereof I affix my signature in presence of two witnesses.

EDMUND SUCKOW.
